UNITED STATES PATENT OFFICE.

JAMES A. WHITCOMB, OF McALESTER, OKLAHOMA.

TYPE-WRITING MACHINE.

1,126,147.

Specification of Letters Patent. Patented Jan. 26, 1915.

Application filed July 14, 1910. Serial No. 571,903.

To all whom it may concern:

Be it known that I, JAMES A. WHITCOMB, a citizen of the United States, and a resident of the city of McAlester, in the county 5 of Pittsburg, State of Oklahoma, have invented certain new and useful Improvements in Type-Writing Machines, of which the following is a specification.

This invention relates broadly to type-writing machines and more specifically to platen shifting mechanism for typewriting machines, wherein the platen is shifted to upper and lower case printing positions through the segment of an arc.

The principal object of this invention is to provide a construction for a typewriting machine of the folding type in which the carriage and attendant mechanisms are mounted in the machine frame in such manner as to be folded over to abnormal position and the construction of parts being such that the pivotal point about which the carriage is folded from normal to abnormal positions, becomes the pivotal point about which the 25 carriage is shifted when it is moved from lower case printing position to capitals or to a third printing position for figures and characters.

A further object of the invention is to construct a typewriting machine in such manner that the platen is shifted through a segment of an arc when it is moved from one printing position to another, the radius of said arc being substantially one-half the 35 length of the typewriting machine frame.

Another object of the invention is to construct a typewriting machine of the folding type in such manner that the side bars upon which the carriage is supported, are pivoted to the upper middle portion of the machine frame in such manner as to permit the platen and carriage mechanism to be folded to abnormal position and the construction of parts being such that the side 45 bars are moved through a segment of an arc when the carriage is shifted from one printing position to another.

A further object of the invention is to construct a typewriting machine in such manner that the carriage is moved from one printing position to another by means of pivoted supports located substantially at the upper middle portion of the sides of the machine frame, and counterbalancing springs 55 on each side of the machine frame having

operative connection with the pivoted supports upon which the carriage is moved from one printing position to another.

A still further object of the invention is to construct a typewriting machine in which 60 the carriage is adapted to occupy a plurality of printing positions and having each printing position, other than the normal printing position, determined by adjustable cam controlled stop screws.

A still further object of the invention is to construct a typewriting machine in such manner that the carriage is adapted to occupy a plurality of printing positions, shift keys for moving the carriage from one 70 printing position to another, and one of the shift keys being constructed to change the relation of the stops and simultaneously lift the carriage mechanism.

A still further object of the invention is 75 to construct a typewriting machine in such manner that the platen carriage may assume a plurality of printing positions and be locked in each printing position, the locking mechanism being constructed in such 80 manner as to support in locked position each of the carriage supporting links.

Still further objects of the invention will in part be obvious and will in part be pointed out in the specification, by reference to 85 the accompanying drawings and will be more specifically defined in the claims hereinafter following.

Throughout the specification and the several figures of the drawings, like numerals 90 have been used to indicate like parts.

In the drawings:—Figure 1 is a sectional elevation taken on lines A—B of Fig. 3, and showing the platen shifting mechanism at the left of the machine frame in its normal 95 position. Fig. 2 is a view similar to Fig. 1, with the exception that the platen shifting mechanism is shown in its extreme elevated position. Fig. 3 is a transverse cross section taken on lines C—D of Fig. 1, showing 100 the carriage, ribbon, and feed mechanism, etc., in elevation. Fig. 4 is a plan sectional view taken on lines E—F of Fig. 3, showing the relationship of the key levers in the machine frame. Fig. 5 is a detail 105 elevation of the locking lever for the shift bell crank on the right of the machine frame.

The typewriting machine illustrated in the drawings and to which my platen shift mechanism invention is particularly adapt- 110

ed, is a typewriting machine of the folding type, as is indicated particularly by the relationship of parts shown in dotted lines in Fig. 1 of the drawings, wherein side bars 1 and 2 are pivoted to the upper middle portion of the sides of the machine frame 4, by means of stud bolts 5 and 6, respectively. The side bars 1 and 2 are adapted to support a carriage bed 7, upon which a carriage frame 8 is mounted for reciprocal motion upon anti-friction rollers 9, 10 and 11. A cylindrical platen 12 is mounted in the carriage frame 8, which carriage frame also provides a mounting for the usual paper feed mechanism 14. The cylindrical platen 12, is provided with the usual line spacing mechanism 15, which is indicated at the left of the platen in Fig. 3 of the drawings. The platen 12 is also provided at its right hand end with a turning knob 16, beneath which a releasing lever 17 is adapted to extend in an upward direction. Ribbon spools 19 and 20, are carried upon the side bars 1 and 2 respectively, and are provided with actuating mechanism which consists in ratchet wheels 21 and 22 respectively, the ratchet wheels being engaged by actuating dogs which are carried upon actuating levers 24 and 25. A cross rod 26, is pivotally mounted between the sides of the machine frame 4, by means of stud screws 27 and 28, and which screws are retained in definite positions of adjustment by means of lock nuts 29 and 30. The cross rod 26 is adapted to carry platen shift bell cranks 31 and 32. The platen shift bell crank 31 is located near the right hand side of the machine frame and the platen shift bell crank 32 is located in similar relationship near the left hand side of the machine frame. A connecting rod 34, is carried between the rear ends of the platen shift bell cranks 31 and 32, and forms a connecting truss between the platen bell cranks and substantially stiffens the platen shifting structure. Platen shift links 35 and 36 are mounted on the rear ends of the platen shift bell cranks 31 and 32 respectively. The platen shift links 35 and 36, are provided with elongated openings 37, through which T-shaped heads integral with anchor studs 38 and 39, are adapted to pass, and form a guiding means for retaining the platen shift links in proper relationship when the carriage is shifted to one of the several printing positions. Each of the platen shift links 35 and 36 are bifurcated at their upper ends, and the bifurcations upon the links are adapted to engage studs 40 and 41, which are fixedly mounted upon the side bars 1 and 2 respectively. The platen shift link 36, is provided at its upper end with a latch member 42, which engages the stud 41, thus preventing the carriage and attendant mechanism from being accidentally swung to folding or abnormal position.

The latch 42 is retained in proper relation by means of a leaf spring 44, carried by the platen shift link 36, and co-operating with the latch 42 in order to retain it in position against a stop pin 43. Lever links 46 and 47, are carried upon the connecting rod, and thus are shifted in a longitudinal direction when the platen shift bell cranks are raised in order to shift the carriage from one printing position to another. The lever links 46 and 47, are guided by stud members 48 and 49, that are fixedly mounted upon bell cranks 50 and 51, which are pivotally mounted upon brackets 52 and 54, that are attached to the rear walls of the machine frame. The bell cranks 50 and 51 carry on their outer ends, suspension links 55 and 56. A universal bar 57, is adjustably mounted upon the lower ends of the suspension links 55 and 56, by means of pairs of adjusting nuts 58 and 59, and is adapted to overlie the ends of the key levers (not shown in the drawings) in such manner that the universal bar is actuated each time a printing key lever or space lever is depressed. A cross bar 60, is carried between the upper ends of the lever links 46 and 47, and maintains the lever links in proper fixed relationship in such manner that the upper ends of the lever links 46 and 47 are in proper position to engage the actuating levers 24 and 25 respectively, in order to operate the ribbon spools. Key lever fulcrum rods 61, 62 and 64, are carried between the side walls of the machine frame and form pivotal supports for the several keys of the key board (not shown). The platen shift keys 65 and 66, are carried upon the key lever fulcrum rods 61 and 63 respectively. The platen shift key 65, which is the key that positions the platen carriage in intermediate or "cap" position, carries upon its rear end a connecting link 67, which operatively connects the "cap" shift key with the platen shift bell crank 32, by means of a pin 68, which co-operates with the lower end walls of a slot 69 formed in the lower end of the link 67. The "fig" platen shift key 66, is carried upon the key lever fulcrum rod 61, and is connected with the platen shift bell crank 32, by means of a connecting link 70, which co-operates with a pin 71, carried by the platen shift bell crank 32, and which is adapted to engage the lower end wall of a slot 72, formed in the lower end of the link 70. Key lever springs 74 and 75, are attached to a type bar rest 76, and engage the platen shift keys 65 and 66 respectively, in order to maintain the platen shift keys in normal position. A front board 77, is mounted forward of the key lever springs 74 and 75 and the type bar rest 76, and extends between the side walls of the machine frame in order to protect and cover up the more delicate portions of the typewriter key lever con-

structure. Brackets 78, are fixedly mounted on each side of the machine frame beneath the type bar rest 76, and form abutments wherein adjustable anchors 79 hold one end 5 of each of two counterbalancing coiled springs 80, which at their other ends are attached to the upper arms of the bell crank shift levers 31 and 32 respectively, in order to counterbalance the weight of the platen 10 carriage, and attendant mechanism, when the carriage is shifted to one of the shift positions for printing either numerals or capitals. A cam actuated stop member 81, is pivotally mounted at 82, to the left hand 15 side of the machine frame, and carries upon its upper ends adjustable stop members 84 and 85. A cam face 86, is formed upon the front portion of the cam actuating stop member 81, and is adapted to rest against 20 a cam actuating pin 87, that is carried by the outer end of the "fig" shift lever 66. An abutment shelf 88, is formed upon the forward edge of the platen shift link 36, and is adapted to contact with either of the 25 adjustable stops 84 or 85, depending upon which of the said stops is positioned in the path of the abutting shelf. When the "cap" shift key is depressed, the lower wall of the link 67 contacts with the pin 65, and 30 the bell cranks 31 and 32 are lifted, since they are both formed integral with the cross rod 26, and the platen is lifted to intermediate "cap" position by means of the platen shift links 35 and 36 coöoperating with the 35 studs 40 and 41 carried upon the side bars 1 and 2. The adjustable stop 85, is held directly in the path of the abutting shelf 88, upon the shift link 36, by means of the leaf spring 89, which is attached to the rear wall 40 of the machine frame and presses against the rear edge of the cam actuated stop member 81. When the "fig" shift key is depressed, the bell cranks 31 and 32 are raised 45 through the connecting link 70, which contacts with the pin 71, and the platen carriage is moved upward by the members which have hereinbefore been described in connection with the lifting of the platen carriage, by the "cap" shift key. As the "fig" shift 50 key is depressed, a cam actuating pin 87, rides over the cam face 86 on the cam actuated stop member, swinging the stop member rearwardly about the pivot 82, until the adjusting stop 84 is positioned in the 55 path of the abutting shelf 88. The contact of the abutting shelf 88 and the short adjustable stop 84, determines the position of the platen with reference to the printing position for characters, numerals, etc. It will 60 be noted that the platen shift bell cranks 31 and 32, are lifted through a greater angle by the action of the "fig" shift key, than the lift which is accomplished by operating the "cap" shift key. However, when the 65 carriage is shifted to either of the shifted

positions which it is adapted to occupy, it will be noted that it shifts upon the side bars 1 and 2 as they swing upon the pivotal stud bolts 5 and 6, and thus the carriage is shifted through an arc the radius of which 70 is substantially the length of a type bar in the machine, or substantially one-half the length of the side of the machine frame.

It will also be noted that the carriage shifts when being moved from one printing 75 position to another, about the same pivotal point around which the carriage is adapted to swing when being folded from normal to abnormal position in order that the machine frame may be packed in small compass for 80 purposes of transportation. During the time when the carriage is shifted from one printing position to another, the side bars 1 and 2 lie between extensions 91, which are formed upon the rear portions of the side members 85 of the machine frame 4. It will be noted that the platen shifting structure is very strong, and that the platen is definitely and positively guided during the change of position from one printing position to another, 90 and is fixedly held in definite position in either of the printing positions.

In using a typewriter it frequently becomes desirable that the platen carriage may be definitely locked in any one of the shifted 95 positions, and in order to accomplish this function I have provided a locking member on the sides of the machine frame. An actuating lever 92, is fixedly mounted upon a cross rod 94, which is pivoted to turn upon 100 bearings arranged in the machine frame. The lower end of the actuating lever is formed in the nature of a bell crank having wedge faces 95 and 96 formed thereon, which are adapted to engage a locking pin 97, fixedly mounted upon the platen shift bell crank 32. The cross rod 94, is curved downwardly as at 98 and 99, in order to pass under the key levers (not shown) in such manner as not to interfere with their action, and 105 carries on the end opposite to the locking lever 92, a locking member 100, the construction of which is substantially the same as the lower portion of the locking lever 92, and is formed with wedge faces 101 and 103, 110 which are adapted to engage a locking pin 104, that is carried upon the bell crank 31. Since both the locking lever 92 and the locking member 100, are fixedly mounted upon the cross rod 94, they will simultaneously 115 engage with the locking pins 97 and 104, thus supporting each side of the platen carriage in a definite locking relation with reference to either of the platen shift positions. Heretofore in machines of this type, the 120 platen has been locked at different printing levels by locking only the mechanism which is adapted to support one end of the carriage bed. In such construction the weight of the carriage bed and mechanisms mounted there- 125 130

upon, is sufficient to cause the other end of the carriage bed to drop a small degree below printing level. The result of this is to spoil the vertical alinement of printing. In 5 the construction which I have herein described and shown in the drawings, it will be noted that each end of the carriage bed is positively locked and supported in either of the printing levels to which the platen may 10 be shifted, and thus it will be seen that this mechanism obviates the dropping of the carriage bed due to the fact that one side is not positively supported when the platen is locked in one of the higher printing levels. 15 Having thus described my invention what I claim as new and desire to secure by Letters Patent is:—

1. In a typewriting machine of the folding type in combination, a machine frame, 20 side bars pivoted to the upper middle portion of said machine frame, a carriage bed carried by said side bars, a platen carriage mounted for reciprocal motion on said carriage bed, a platen mounted in said platen carriage, and key actuated means for shifting said side bars in order that the platen may be moved to different printing positions.

2. In a typewriting machine of the folding type in combination, a machine frame, 30 side bars pivotally mounted on the upper middle portion of said machine frame, a carriage bed carried upon said side bars, a platen carriage mounted for reciprocal motion upon said carriage bed, a platen mounted 35 in said platen carriage, key board mechanism for swinging said side bars to move said platen to various printing positions, and means for limiting the distance through which said side bars are moved.

40 3. In a typewriting machine of the folding type in combination, a machine frame, side bars pivotally mounted upon the upper middle portion of said machine frame, a carriage bed carried by said side bars, a platen carriage mounted for reciprocal movement upon said carriage bed, a platen mounted in said platen carriage, key operated mechanism for moving said side bars to move the platen to a definite printing 45 position, and a second key operated mechanism for moving the side bars to move the platen to a second definite printing position.

4. In a typewriting machine of the folding type in combination, a machine frame, 50 side bars pivoted to the upper middle portion of said machine frame, a carriage bed carried by said side bars, a platen carriage mounted for reciprocal motion upon said carriage bed, a platen mounted in said platen carriage, bell cranks mounted in said machine frame, shift links operatively connecting said bell cranks and said side bars, counterbalancing springs anchored to said machine frame and attached to said bell 55 cranks, and key operated means for shifting

said bell cranks to move the platen to different printing positions.

5. In a typewriting machine, the combination of a machine frame, a carriage bed, pivotal carrying means for said carriage bed, said pivotal means being attached to the machine frame and extending substantially one-half the length thereof, a platen carriage mounted for reciprocal movement upon said carriage bed, a platen mounted 70 in said platen carriage, key actuated means for shifting said platen from one printing level to another, the construction and arrangement of parts being such that the platen moves through a vertical arc, the 75 radius of which is substantially one-half the length of the machine frame when the platen is shifted from one printing level to another.

6. In a typewriting machine of the folding type, the combination of side bars pivoted to the machine frame, a carriage bed mounted upon said side bars, a platen carriage mounted for reciprocal movement upon said carriage bed, a platen carried 80 by said platen carriage, and key actuated means in operative relation to said side bars when they are in normal printing position, to move said side bars in such manner as to translate the platen from one printing level 85 to another, substantially as described.

7. In a typewriting machine in combination, a machine frame, bell cranks mounted in said machine frame, a carriage bed pivotally mounted upon said machine frame, a 100 platen carriage mounted upon said carriage bed, a platen carried by said platen carriage, links operatively connecting said bell cranks with said carriage bed, counterbalancing springs having one of their ends 105 anchored to the machine frame and the other one of their ends attached to the bell cranks, a shift key operatively connected with one of said bell cranks in such manner as to shift the said platen carriage from 110 one printing level to another, and a second shift key operatively connected with one of said bell cranks in such manner as to shift the platen carriage to a different printing 115 level.

8. In a typewriting machine in combination, a machine frame, a carriage bed pivotally mounted on said machine frame, a platen carriage mounted upon said carriage bed, a platen mounted upon said platen carriage, bell cranks mounted in the machine frame, shift links operatively connecting said bell cranks with said platen carriage, counterbalancing springs attached to the machine frame and to the bell cranks, a key 120 member, a slotted link connecting said key member with one of said bell cranks, a second key member and a second slotted link connecting said second key member with one of said bell cranks, and movable means 125 130

- for determining the limit to which said key members may shift the platen.
9. In a typewriting machine in combination, a machine frame, a carriage bed pivotally mounted upon said machine frame, a platen carriage carried by said carriage bed, a platen mounted in said platen carriage, a pivotally mounted cross rod, bell crank members fixedly mounted upon said cross rod, links operatively connecting said bell cranks with said carriage bed, and key mechanism attached to one of said bell cranks for shifting said platen from one printing level to another.
10. In a typewriting machine in combination, a machine frame, side bars pivotally mounted upon said machine frame, a carriage bed carried by said side bars, a platen carriage mounted upon said carriage bed, a platen mounted in said platen carriage, key actuated means for shifting said side bars through a vertical arc in order to position the said platen in different printing levels, and means integral with said machine frame for guiding said side bars in their vertical movement.
11. In a typewriting machine in combination, a machine frame, a carriage bed pivotally mounted upon said machine frame, a platen carriage mounted upon said carriage bed, a platen carried by said platen carriage, vertical links operatively connected with said carriage bed, a stop formed on one of said vertical links, a pivotally mounted stop carrier, adjustable stops upon said stop carrier, a cam face upon said stop carrier, key actuated means for shifting said vertical links in order to move the platen from one printing level to another, a portion of said key actuated means coöperating with said cam face in order to determine which of said adjustable stops shall coöperate with the stop on said vertical link when the platen is shifted to different printing levels.
12. In a typewriting machine in combination, a machine frame, a carriage bed pivotally attached to said machine frame, a platen carriage mounted upon said carriage bed, a platen mounted in said platen carriage, vertical links operatively connected with said carriage bed, a stop formed upon one of said vertical links, a stop carrying member pivotally mounted upon said machine frame, adjustable stops carried by said stop carrying member, a cam face formed upon said stop carrying member, key actuated means operatively connected with said vertical links for moving said platen to a second printing level, a second key actuated means operatively connected with said links for moving the platen to a third printing level, said second mentioned key actuated means comprising means coöperating with said cam face in order to position said stop carrying member in such manner as to deter-
- mine the height to which the platen is moved in arriving at the third printing level.
13. In a typewriting machine in combination, a machine frame, a carriage bed, a carriage mounted for reciprocal motion upon said carriage bed, a platen mounted in said platen carriage, vertical shift links operatively connected with the carriage bed near each end thereof, means for moving said links in a vertical direction in order to move the platen from one printing level to another, and means for locking each of said vertical links in their elevated position.
14. In a typewriting machine in combination, a machine frame, side bars pivotally mounted upon said machine frame, a carriage bed mounted upon said side bars, a platen carriage mounted for reciprocal movement upon said carriage bed, a platen carried by said platen carriage, key actuated means for shifting said side bars to position said platen in different printing levels, said key actuated means including vertical shift links operatively connected with said side bars, and means for locking said vertical shift links in either of their shifted positions, said locking means including a key operated stop member.
15. In a typewriting machine in combination, a machine frame, side bars pivotally mounted upon said machine frame, a carriage bed mounted upon said side bars, a platen carriage pivotally mounted upon said carriage bed, a platen carried by said platen carriage, bell crank members mounted in said machine frame, vertical shift links operatively connecting said bell crank members and said side bars, lock pins carried by each bell crank member, locking arms adapted to engage said lock pins, and means for actuating said locking arms, substantially as described.
16. In a typewriting machine in combination, a machine frame, side bars pivotally mounted upon said machine frame, a carriage bed carried by said side bars, a platen carriage mounted for reciprocal movement upon said carriage bed, a platen mounted in said platen carriage, a cross shaft rod mounted in said machine frame, bell crank members mounted upon said cross shaft, vertical links operatively connecting said bell cranks with said side bars, key actuated means for moving said bell cranks in order to position said platen in different printing levels, stop mechanism for determining the vertical movement of said platen, and locking mechanism coöperating with each bell crank in order to lock said platen in any printing level to which it may be shifted.
17. In a typewriting machine in combination, a machine frame, side bars pivotally mounted upon said machine frame, a carriage bed mounted upon said side bars, a

platen carriage mounted upon said carriage bed, a platen carried by said platen carriage, a cross shaft mounted in said machine frame, bell crank members mounted at substantially each end of said cross shaft, means operatively connecting said bell cranks with said side bars, means for shifting said bell cranks in order to position said platen in different printing levels, and means for simultaneously locking each bell crank in order to hold said platen in any printing level to which it may have been shifted.

18. In a typewriting machine in combination, a platen, means operatively connect-

ed with said platen to guide said platen to swing in an arc when said platen is raised or lowered, key operated means including vertical shift links for moving said platen from one printing level to another, an oscillating plate carrying a plurality of stops, a cam attached to said plate, and means co-operating with said cam to shift said laterally movable plate when the platen is swung to its highest printing position.
